CLAIM

The ornamental design for a beverage straw as shown and described.

DESCRIPTION

FIG. 1 is a top perspective view of a beverage straw showing our new design.

FIG. 2 is a bottom perspective view thereof.

FIG. 3 is a right side elevational view thereof.

FIG. 4 is a front elevational view thereof.

FIG. 5 is a rear elevational view thereof.

FIG. 6 is a left side elevational view thereof.

FIG. 7 is a top plan view thereof.

FIG. 8 is a bottom plan view thereof.

FIG. 9 is a top perspective view of a second embodiment thereof.

FIG. 10 is a bottom perspective view thereof.

FIG. 11 is a right side elevational view thereof.

FIG. 12 is a front elevational view thereof.

FIG. 13 is a rear elevational view thereof.

FIG. 14 is a left side elevational view thereof.

FIG. 15 is a top plan view thereof; and,

FIG. 16 is a bottom plan view thereof.

The broken lines depict environment that forms no part of the claimed design.

1 Claim, 14 Drawing Sheets

Related U.S. Application Data

No. 29/802,545, filed on Aug. 5, 2021, now Pat. No. Des. 984,854, which is a division of application No. 29/713,503, filed on Nov. 15, 2019, now Pat. No. Des. 929,183.
